UNITED STATES PATENT OFFICE

2,524,580

SKATE CLAMP

George Walton, Oak Lawn, Ill.

Application September 19, 1945, Serial No. 617,294

3 Claims. (Cl. 280—11.33)

1

The present invention relates to a skate clamp and more particularly to a clamp for the toe portion of a skate which clamp may be tailored to suit the whims and desires of a particular skater and which constitutes a permanently adjusted clamp for the toe of the shoe.

There are many skaters, among the professionals and exhibitionists, who desire to have their skates removably applicable to their shoes. In this connection such skaters demand that the skates be firmly attached to the shoes while skating.

Many of such skaters prefer to have the clamps for the toe portions of the skates permanently adjusted so that the skates may be quickly applied and removed and when applied be properly clamped to the shoes.

An object of the present invention is to provide a skate clamp which may be permanently adjusted to the shoe of a skater at a minimum expenditure of time on application of the clamp, and which is highly efficient in use.

Another object of the present invention is to provide a skate clamp for the toe portion of a skate which may be individually fitted to the shoe of a skater and permanently adjusted to such shoe and in which the forces tending to separate the ends of the toe clamp are resisted by engagement of the clamp with some portion of the skate support, thus relieving the attaching rivets of any stresses in shear.

A further object of the present invention is to provide a one-piece member which may be readily applied to a skate for engaging the toe portion of a shoe, and which may be formed to permanent shape for receiving such shoe and securing it firmly to the skate.

The above, other and further objects of the invention will be apparent from the following description and accompanying drawing.

An embodiment of the present invention is illustrated in the accompanying drawing and the views thereof are as follows:

Figure 1 is a side elevational view of a shoe with a skate thereto applied, the skate being provided with the novel toe clamp of the present invention;

Figure 2 is a plan view of the member utilized for the skate clamp of the present invention;

Figure 3 is a fragmental view of the underside of a skate plate, showing the clamp member of the present invention thereto applied and illustrating how the resistance to the tendency of the ends of the clamp to spread is resisted by a structural portion of the skate;

2

Figure 4 is a front end view of the plate showing the clamp thereto applied as it appears in permanently adjusted relation;

Figure 5 is a plan view of the heel of a skater's shoe showing an attaching plate threaded in the heel to receive attaching means for the heel to the skate; and

Figure 6 is a vertical sectional view taken in the plane of line 6—6 of Figure 5.

10 It is to be understood that when a skate is equipped with a skate clamp permanently adjusted to receive the toe end of a shoe, suitable means must be provided for attaching the heel portion of the skate to the heel of the shoe.

15 The drawing will now be explained.

The device of the present invention is illustrated in connection with one type of a roller skate, but it is apparent that the device may be used also with various types of ice skates and other types of roller skates, the type chosen being exemplary only.

Figure 1 illustrates a shoe 10 attached to a roller skate having a foot plate 11 supported by the usual rollers 12 which are carried in brackets, front bracket 13 and rear bracket 13a. Cushions 14 are interposed between the roller axles and the brackets to minimize jar while skating over rough surfaces and to afford flexibility of the roller mountings. The front brackets 13 constitute medianly disposed protuberances on the under sides of the foot plates 11. The bracket 13 has an upper rounded portion 13b that slopes upwardly to the rear to flat strap 13c. A depending strut 13d of oval cross-section connects the portion 13b to the wheels.

The brackets are suitably reinforced by a strut 15 which co-operating with the brackets constitutes a truss supporting structure for the foot plate 11.

40 Figure 2 illustrates in plan the one-piece member utilized for forming the skate clamp for the toe portion of the skate. The member A is a metal strap, of suitable width, and is notched at 16, at mid-length, and then bent at 17 so that the end portions 18 and 19 make a wide obtuse angle with each other. Two rivet holes 20 are provided for attachment of the member A to the underside of the plate 11, as illustrated in Figure 3.

45 Suitable mechanism may be provided for securing the heel portion of the skate to the heel of the shoe. It is to be understood, however, that this attaching means must be such that the skate may be applied to the shoe by a straight line 55 pull in the direction of the length of the shoe

to cause the skate clamp for the toe portion of the skate to tightly engage the shoe and then secure the heel portion of the skate to the heel without further movement of the skate with respect to the shoe.

The heel attaching means herein disclosed will now be described. Figure 6 is an enlarged view of the heel 21 of the shoe. The heel has a double well bore formed in it, the inner or smaller bore 22 extending into the heel, and the outer or larger bore 23 is shallow and receives an attaching plate 24 in such manner that the outer surface thereof is flush with the bottom of the heel 21. The plate 23 is provided with a slot to receive the head 25 of an attaching means, which head is provided with a cross pin 26. The slot in the plate 24 is shaped to receive the head 25 and the pin 26. The head 25 has a spindle 27 extending through the plate 11 of the skate to which is applied a lever 28 for rotating the head 25 to move the pin 26 thereof out of engagement with the slot in the plate 24, when the skate is applied to the shoe, so that the pin 26 will engage the recess side of the plate 23 and lock the heel portion of the skate to the shoe.

After a shoe has been provided with means for attaching the heel thereof to the heel portion of the skate, the shoe is applied to the skate and then the member A is applied to the under surface of the front end of the plate 11 with the notch 16 thereof snugly fitting about the front bracket 13, as illustrated in Figure 3. Rivets 30 are then passed through the rivet holes 20 in the member A and through suitable holes in the plate 11 to attach the member A to the under surface of the plate 11 of the skate. The extremities of the portions 18 and 19 of the member A are then bent upwardly and inwardly, as illustrated in Figure 4, to provide end members for engaging over the side margins of the toe of the shoe, as shown in Figure 1, and as is customary.

The extremities of the member A are so shaped that the toe portion of the shoe is tightly gripped by the member A, firmly holding the skate to the shoe.

When a skate is tightly applied to a shoe, stresses are set up tending to separate the ends 29 of the member A. While these stresses are not great, nevertheless they exist. The unitary structure of the clamp of this invention helps the rivets 30 to resist this tendency to pull the clamp apart. The unitary structure, therefore, gives added strength to the clamp.

It is apparent that utilization of the skate clamp member A, of the present invention, lends itself very readily to individual likes of skaters, in having the toe portions of their skates permanently adjusted and when adjusted, firmly fixed against any likelihood of looseness subsequently occurring.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A skate having a foot plate with a medianly disposed protuberance on its under side, a one-piece toe clamp member across the under side of said plate and having a notch snugly fitting said protuberance and with its ends bent upwardly and inwardly to receive the sole of a shoe and constituting a permanently adjusted toe clamp member, and rivets securing said member to said plate.
2. In combination in a skate, a foot plate, supporting means for said foot plate including a bracket depending from the forward central portion of said foot plate, a one-piece member bent substantially at mid-length as a wide obtuse angle and having its ends turned upwardly and inwardly to receive the toe portion of a shoe to constitute a permanently adjusted toe clamp, said member having a notch for receiving the depending bracket of said supporting means for centering said member and rivets securing said member to said foot plate.
3. As an article of manufacture, a shoe clamp for a skate, having a sole plate and a bracket depending from the forward central portion of said sole plate, comprising an elongated metal strap having a notched portion substantially at the longitudinal mid-point thereof for receiving the bracket in snug abutting relation for centering the clamp on the skate, the portions of said strap on either side of said notch extending outwardly and forwardly therefrom and having end portions foldable upwardly and inwardly for wedgingly receiving the toe portion of a shoe.

GEORGE WALTON.
